UNITED STATES PATENT OFFICE.

GEORGE W. LEEMING, OF BIRMINGHAM, ALABAMA.

WIND-SHIELD SHADE.

1,290,588.

Specification of Letters Patent.

Patented Jan. 7, 1919.

Application filed February 1, 1918. Serial No. 214,940.

To all whom it may concern:

Be it known that I, GEORGE W. LEEMING, a citizen of the United States of America, residing at Birmingham, in the county of 5 Jefferson and State of Alabama, have invented certain new and useful Improvements in Wind-Shield Shades, of which the following is a specification.

My invention relates to a combined wind 10 shield and shade in which a shade roller especially designed for the purposes is incorporated in the top cross member of the upper wind shield section having a rod at the free end of the shade adapted to be received 15 and to travel in guides formed in the sides of the frame of the top wind shield section.

The purpose of my invention is to so incorporate a shade in the wind shield that it will be comparatively inexpensive and always 20 instantly available to be drawn down so as to shield the eyes of the driver from the glare of lights ahead.

It is my purpose to so design the shade that it will be compact, can be lowered to 25 the desired position and released instantaneously with the use of but one hand and which will hang in position without fluttering or being objectionable in any way.

I preferably employ the well known type 30 of spring shade roller having the automatic detent which will arrest the shade when lowered to the desired position. This roller is preferably reduced to a minimum in diameter so that when the shade is rolled thereon 35 it can be readily received in the tubular upper member of the wind shield frame without unduly enlarging the latter or affecting the appearance of the wind shield.

My invention further embodies the various 40 details of construction and arrangements of parts, which in their preferred embodiments are illustrated in the accompanying drawings, in which:—

Figure 1 is a perspective view of a standard type of wind shield equipped with my protecting shade in partly lowered position.

Fig. 2 is an enlarged view broken away showing the shade roller and the frame casting in which it is mounted.

Fig. 3 is a sectional view taken on the line 3—3 of Fig. 1.

Fig. 4 is a vertical sectional view taken on the line 4—4 of Fig. 5.

Fig. 5 is a detail view of the flattened end 55 of the shade rod.

Fig. 6 is a plan view of the blank from

which the specially designed upper section of the wind shield frame is formed.

Similar reference numerals refer to similar parts throughout the drawings. 60

I have illustrated my invention as incorporated in a wind shield comprising a lower section 1 and an upper section 2, both of which are pivotally connected by pivot pins 3 to the supports 4 mounted on the dash of 65 the car. The lower wind shield section 1 may be of any standard design but the frame for the upper wind shield section is especially designed for receiving and guiding my shade. As shown in Figs. 2 and 4, the 70 glass 5 for the upper wind shield section has its edges mounted in a U-shaped brass retaining strip 6 having an outturned flange 7 on the front side of the glass. This strip with its internal felt lining 6^a is continuous 75 about the ends and top edges of the glass, and constitutes the glass holder proper. Along the side edges the strip is adapted to be received in a channel shaped frame 8 which seats flush against the flange 7 but has 80 its other edge spaced sufficiently from the rear edge of the strip 6 to form a vertical guide way 9 in which the flattened ends 10 of the bottom shade rod 11 are received and guided. The top member of the frame is 85

formed by a tubular member 12 having plugs 13 and 14 made fast in its ends. The plug 14 is provided with a rounded socket bearing with a sleeve extension 14^a which receives the round end of the roller shaft 15 which 90 has a flattened end 16 that fits into the correspondingly shaped opening in the head 13 and is held thereby against rotation. A shade roller 17 is mounted to turn on the shaft 15 and is pressed by means of a coil 95

spring 18 in a direction to wind thereon the shade 19. The well known gravity latch mechanism 20, such as is employed on all window shades, is here provided so that the roller may be brought to rest when the 100 shade has been lowered to the desired point and there held against the action of the spring until the latch is tripped, when the speed of the roller will prevent the latch again operating before the shade has been 105 entirely wound on the roller. This mechanism being well understood in the art and forming no particular part of my invention, has not been illustrated in detail. The shade roll is held in position by the collar 14^a at 110 one end and a set collar 14^b at the other end.

The outer edge 21 of the top section 12

rests on the flange 7 of the brass strip while the other edge 22 of the member 12 is spaced from the rear edge of said member and slightly out-turned. The spacing is such 5 that the rod 11 at the base of the shade will not pass this portion 22 when the shade is permitted to run up to concealed position. The shade itself is preferably interrupted at its center as indicated at 23 to leave the rod 10 exposed so as to form a hand grip for conveniently manipulating the shade.

In Fig. 6 I show the preferred manner of forming my frame. Here the blank comprises a main body portion 24 having at its 15 corners oppositely extending strips 25. The shade casing 12 is formed from the body 24 and the strips 25 on each end of the body are shaped and drawn together to jointly form the channel shaped sides 8, the sections of each side being secured at their upper ends by the bearings 3, which are brazed or welded thereto, and at their lower ends by the corner clips 26, Fig. 2.

In operation, the shade is responsive to 25 the tension of spring 18 when normally run up to concealed position, in which however the hand grip portion 23 of its rod is convenient to be grasped by one hand of the driver. If any circumstance arises wherein 30 a glare is created on the wind shield tending to blind the driver, the latter grasps and draws the shade down to its lowered position over the upper section of the wind shield, thus forming a protection for his 35 eyes while he can see under the shade a sufficient distance ahead for the safe driving of the car.

While it is preferable that the shade shall be incorporated in the wind shield frame

proper, it may obviously be mounted as an 40 attachment on present wind shield frames.

Having thus described my invention, what I claim as new and desire to secure by Letters Patent, is:—

1. The combination with a wind shield 45 frame comprising a tubular top member and inturned channel-shaped side members, a frame for the glass mounted in the said channel members of said frame with its back face spaced from the rear edges of the side 50 and top of said frame, a spring-pressed shade roller mounted in the tubular top section of the frame above and in the same plane with said glass frame, a shade on said roller, and a rod at the free end of the shade 55 having its ends guided between the adjacent side members of said frames.

2. In a wind shield, the combination with a glass and its marginal binder strip, of a top frame section comprising a tubular top 60 and channel shaped side members, said frame being seated against and fitted about said binder strip but having the rear edges of its channel members spaced from the rear edges of the strip to form vertical side 65 guides and having the rear edge of the tubular top member spaced sufficiently from said strip to form a shade outlet slot, a spring-pressed shade roller mounted in said top tubular member, a shade wound thereon and 70 projecting through said shade slot, and a rod on the free end of the shade which works in the side guides and is adapted to be arrested by the top member, substantially as described.

In testimony whereof I affix my signature.

GEORGE W. LEEMING.
